SOUND-BOX FOR SOUND-REPRODUCING MACHINES

Application filed January 14, 1932, Serial No. 586,661, and in Germany January 13, 1931.

This invention refers to improvements in sound-boxes for sound-reproducing machines and is designed for the type, where the record-grooves are utilized for feeding the sound-box across the record.

The invention is applicable to mechanical as well as electrical sound-boxes, in the first instance a diaphragm, in the latter an armature being actuated by the stylus-bar.

10 In sound-boxes for sound-reproducing machines of the type where the record-grooves feed the sound-box across the record usually, the stylus-bar is fixed on the case of the sound-box pivotally or by means of spring-joints. When the stylus actuates the diaphragm by employing the stylus-bar as a lever, back-pressure is exercised upon its bearings, pivots or springs, with the effect of causing vibrations of the sound-box as a whole as well as the tone-arm. Spring-joints moderate these vibrations at the expense of volume and accentuation.

According to the present invention the stylus-bar is connected with the sound-box with so considerable a compliance, that only a small fraction of the back-pressure is transmitted to the sound-box itself. Compared with the compliance of the diaphragm the compliance of this connection is very great. Consequently a proper transmission of power to the diaphragm would be impossible without special provisions. For this purpose a push-weight is joined to the stylus-bar, the mass contained in this push-weight being so great that even at comparatively low frequencies it is sufficient to take up the back-pressure by the dynamical reaction of its mass, its impedance. The push-weight is suspended in such a flexible way, that it can easily move and fulfill its purpose as a "floating mass."

One object of this invention is to reduce to a minimum the undesirable vibrations of the sound-box as a whole and the tone-arm.

Another object is to increase the volume of the sound instead of diminishing it by taking up the back-pressure in bearings or ordinary spring-joints. This effect is caused by the phenomenon that the push-weight vibrates in an additive co-action with the movements of the stylus.

A third object of this invention is to extend the response-curve further into the bass, in other words, to use the push-weight for tuning the diaphragm to a frequency below 500 cycles per second.

A fourth object of this invention is to make the sound less metallic and more musical than with ordinary sound-boxes. This result is obtained, because the turning point of the stylus-bar and therefore its ratio of transformation as a lever is not definite any more, but varies with the frequency.

The push-weight may be either fixed to or embodied in the stylus-bar or pivotally joined to it. The latter form is preferred, because with rising frequency the stylus-bar gradually and automatically will shake off the mass of the push-weight to the extent as its impedance increases and use the pivots as turning point. At high frequencies the push-weight stands practically still and the stylus-bar turns in its pivots only.

The accompanying drawing illustrates the invention by way of examples. For the sake of showing the principle of the invention more clearly the drawing has been given a schematical character.

Fig. 1 is a section through a sound-box, no springs being used for transmitting the feeding pressure.

Fig. 2 is the section of a sound-box, where the feeding pressure is transmitted through rubber buffers or springs.

Fig. 3 is a front view of the latter example.

Fig. 4 is an example of an electrical sound-box embodying my invention.

In Fig. 1, A is the case of the sound-box,

B the diaphragm, the centre of which is connected to the stylus-bar D by the coupling spring C. Through the pivots E the push-weight M is joined to the stylus-bar D, the latter being connected to the body of the sound-box A through the pivots F.

It is to be understood, that in any case the pivots indicated may have the form of proper bearings with or without balls or 10 may assume the form of spring-joints.

In Figs. 2 and 3, A is the case of the sound-box, B the diaphragm, D the stylus-bar connected to the centre of the diaphragm B by means of the spring C. The stylus-bar D is again joined to the push-weight M through the pivots E. A connection between the push-weight M and the sound-box A is established close to the centre of the diaphragm through arms M', so that turning moments 15 are avoided and a more perfect elimination of the undesirable vibrations of the sound-box is a whole is effected. For this purpose, a bridge N is fixed across the sound-box. The pivots F and the buffers or springs H 20 serve to transmit the feeding-pressure from arms M'. The pivots F may be omitted with suitable construction of the buffers or springs H. The latter are exceedingly flexible, because they are situated at a very small radius. 25 The push-weight M is divided into two portions suspended on opposite sides of the stylus bar D as shown. The arms M' extend downwardly from the bridge N parallel to the stylus bar D and connect with the two 30 portions of the push-weight M.

Fig. 4 is the vertical section of an electrical sound-box, N being the magnet, O the induction coil, W the armature forming part of the stylus-bar D. The push-weight M is joined to the stylus-bar D by the pivot E and is supported by depending arm M'. K and P are rubber springs. By F and G a ball bearing is indicated of such a construction that play is allowed to the push-weight 40 M through arm M', so that the latter can carry out rotary movements not only round its point of suspension, but also round the centre of gravity S, as well as lateral movements, so that it may assume various modes 45 of motion.

What is claimed is:

1. In a sound-box for sound-reproducing machines of the type where the record-grooves are utilized for feeding the sound-box across the record, a mechanically displaceable element, a yielding stylus-bar connected therewith and a push-weight connected with said mechanically displaceable element and pivotally connected with the stylus-bar.

2. In a sound-box for sound-reproducing machines of the type where the record-grooves are utilized for feeding the sound-box across the record, a mechanically displaceable element, a yielding stylus-bar con-

nected therewith, a pendulum suspended with respect to said mechanically displaceable element, and a push-weight connected with the stylus-bar and said pendulum.

3. In a sound-box for sound-reproducing machines where the record-grooves are utilized for feeding the sound-box across the record, a mechanically displaceable element, a yielding stylus-bar connected therewith, a pendulum connected with said mechanically displaceable element, and a push-weight connected with the stylus-bar and said mechanically displaceable element, said push-weight having such a mass that the back-pressure of the stylus-bar is taken up essentially by 80 the dynamical reaction of the mass of the push-weight.

4. Sound-box for sound-reproducing machines where the record-grooves are utilized for feeding the sound-box across the record comprising a mechanically displaceable element, a stylus-bar connected with said element and yielding to such an extent that only a fraction of the back-pressure is transmitted to said element, and a weighted pendulum connected with said element and pivotally connected with said stylus bar.

5. Sound-box for sound-reproducing machines where the record-grooves are utilized for feeding the sound-box across the record, a vibratory member in said sound-box, a stylus-bar connected with said member, a weighted pendulum connected with said vibratory members and pivotally connected with said stylus-bar whereby said stylus-bar 100 yields to such an extent that its compliance is greater than the compliance of the vibratory member.

6. In a sound-box for sound-reproducing machines of the type where the record-grooves are utilized for feeding the sound-box across the record, a vibratory member, supporting means for said vibratory member, a stylus bar connected with said vibratory member, a weighted pendulum suspended from said supporting means, and a pivotal connection between said stylus bar and said weighted pendulum at a position remote from the connection of said stylus bar with said vibratory member.

7. In a sound-box for sound-reproducing machines of the type where the record-grooves are utilized for feeding the sound-box across the record, a vibratory member, supporting means for said vibratory member, a stylus bar connected with said vibratory member, a bridge-like frame yieldingly connected with said supporting means, a pair of parallel bars extending downwardly from said bridge-like frame on opposite sides of said stylus-bar, a weight on the extremity of each of said bars, and pivotal connections between said stylus-bar and said parallel bars at a position remote from the connection of said stylus-bar with said vibratory member.

8. Sound-box for sound-reproducing machines, where the record-grooves are utilized for feeding the sound-box across the record having a yielding stylus-bar and a push-weight combined with the stylus-bar, the push-weight containing such a mass that by its reaction upon the system, the response-curve attains a maximum below 500 cycles per second.

9. Sound-box for sound-reproducing machines, where the record-grooves are utilized for feeding the sound-box across the record with a yielding stylus-bar and a push-weight, the push-weight being so yieldingly suspended that it may exercise rotary motions with different centers as well as lateral motions.

10. In a sound box for sound reproducing and sound recording machines, a casing, a stylus bar supported with respect to said casing to execute parallel as well as pivotal motions, a push weight pivotally connected to said stylus bar, said push weight having such a mass that through the back pressure of the stylus bar it is set in relevant vibratory motion at useful acoustic frequencies of the bass range.

11. In a sound box for sound reproducing and sound recording machines, a casing, a stylus bar supported with respect to said casing to execute parallel as well as pivotal motions, resilient elements connected with said stylus bar, a push weight pivotally connected to said stylus bar, said push weight having such a mass that through the back pressure of the stylus bar it is set in vibratory motion at useful acoustic frequencies of the bass range, and through the cooperation of said vibrating mass with the stiffness of the stylus bar and the resilient elements connected thereto, the response within the lower end of the useful acoustic frequency range is increased.

12. In a sound box for sound reproducing and sound recording machines, a casing, a stylus bar supported with respect to said casing to execute parallel as well as pivotal motions, resilient elements connected with said stylus bar, a push weight pivotally connected to said stylus bar, said push weight having such a mass that through the back pressure of the stylus bar it is set in vibratory motion at useful acoustic frequencies of the bass range, and through the cooperation of said vibrating mass with the stiffness of the stylus bar and the resilient elements connected thereto, the response for useful acoustic frequencies below 500 cycles is increased.

13. In a sound box for sound reproducing and sound recording machines, a casing, a stylus bar supported with respect to said casing to execute parallel as well as pivotal motions, resilient elements connected with said stylus bar, a push weight pivotally connected to said stylus bar, said push weight having such a mass that through the back

pressure of the stylus bar it is set in vibratory motion at useful acoustic frequencies of the bass range, and through the cooperation of said vibrating mass with the stiffness of the stylus bar and the resilient elements connected therewith, the compliance of suspension of the push weight is considerably greater than the compliance of the stylus bar and the resilient elements connected therewith.
